UNITED STATES PATENT OFFICE.

ERNEST SCHWEIZER, OF BASEL, SWITZERLAND, ASSIGNOR OF ONE-HALF TO WILHELM E. RUDIN, OF BASEL, SWITZERLAND.

BOBBIN-WINDING MACHINE.

Application filed November 24, 1924. Serial No. 751,977.

To all whom it may concern:

Be it known that I, ERNEST SCHWEIZER, citizen of Switzerland; and resident of Basel, in the canton of Basel City and State of Switzerland, have invented certain new and useful Improvements in Bobbin-Winding Machines; and I do hereby declare that the following is a full, clear, and exact description thereof.

- 10 This invention relates to bobbin winding machines and has for its object the provision of a bobbin winding machine for winding bobbins which are conical at both ends, by means of a reciprocating thread guide, 15 whose movement may be gradually diminished with the increasing diameter of the bobbin. For this purpose, the driving movement of the thread guide is taken from an obliquely positioned rotating plate, 20 formed as a cam, by means of an intermediate element controlled from the latter: this intermediate element is adjustably disposed on a slide moving the thread guide in dependence on the bobbin guide, in such manner that with increasing diameter of the bobbin, it is brought nearer and nearer to the axis of rotation of the rotating plate, in order to cause the diminution of the stroke 25 of the thread guide.
- 30 With the above and other objects in view, which will appear as the description proceeds, the invention resides in the novel construction, combination and arrangement of parts substantially as hereinafter described
- 35 and more particularly defined by the appended claims, it being understood that such changes in the precise embodiment of the herein disclosed invention may be made as come within the scope of the claims.
- 40 In the accompanying drawing is illustrated one complete example of the physical embodiment of the present invention constructed according to the best mode so far devised for the practical application of the 45 principles thereof.

The drawing represents one form of execution of the object of the invention, which is particularly adapted for the reeling of shuttle bobbins in ribbon weaving.

- 50 Figure 1 is a side elevation.
Figure 2 is a vertical cross section.
Figure 3 is a vertical longitudinal section.
Figure 4 is a plan of this example of execution.
- 55 The represented coil winding machine is

arranged for the winding of two coils by means of a common reciprocating thread guide *a*. The two coils are driven from two spindle shafts *b* which are rapidly rotated from a large gear wheel *c* by means of the 60 "tooth pinion" *d*. The gear *c* is seated on a shaft *e* together with a gear *f* which is driven from a driving friction gear drive *h* by means of a "tooth pinion" *g*.

The rod *i* of the thread guide *a* is rigidly 65 connected at *i'* with a slide *k*. On it are disposed two separate springs *m* between the slide *k*, and two stationary guide lugs *l*.

On the shaft *e* is fastened an obliquely positioned rotating plate *n* formed as a cam, 70 which is disposed at a definite angle of inclination to the axis of the shaft. Against this plate is supported a roller *o* which is seated on an arm *o'* of a rod *p* acted on by the spring and movable vertically in the slide *k*. 75 Upon the rotation of the plate *n* the same acts on the spring actuated rod *p* in such manner that it reciprocates the slide *k* on the thread guide *a* in order to permit the thread to be wound on to the rotating 80 bobbin spool in known manner.

Beneath each bobbin is arranged a guide roller *r* which is seated on a lever *t* rotatably journaled at *s*, the lever being adjustably connected with a gudgeon *w* at *u'* by means 85 of a lever *u* journaled in a bearing *x* (Figure 2), whereby this gudgeon *w* is rigidly connected with the rod *p* by a head member *w'*.

With increasing thickness of the bobbin, 90 the guide lever *t* gradually swings more and more about a pivot point counterclockwise whereby the gudgeon *w* and with it the rod *p* are gradually moved more and more downward crosswise to the direction of 95 movement of the slide *k* by means of the lever *u* so that the roller *o* more and more approaches the axis of rotation of the rotating plate, and thereby the movement stroke of the slide *k* under the action of the 100 rotating plate *n* is diminished. The consequence of this is that the stroke of the thread guide is gradually and correspondingly diminished, so that in the winding process the bobbins have both ends conical. If the 105 bobbins attain a definite maximum permissible diameter, the guide lever *t* in known manner strikes against a projection of a shut-off rod *y* and causes the machine to be shut off.

2
I claim:

1. A machine for winding conical ended bobbins comprising means for rotating the bobbin, a rotary shaft having an obliquely positioned plate thereon, a thread guide for said bobbin, intermediate mechanism operating said thread guide and having a portion contacting with said plate, and a feeler for said bobbin for moving the contacting portion of said intermediate mechanism towards the center of said rotary shaft as said bobbin increases in diameter.
- 10 2. A machine for winding bobbins conical at both ends, said machine comprising a rotating spindle for said bobbin, a feeler roller paralleling said spindle and contacting with the bobbin, a pivoted lever having one end
- 15

connected to said feeler roller, a cam follower operatively connected to the other end of said lever, an obliquely positioned cam plate for moving said cam follower, and a thread guide reciprocated by said follower, said cam follower being moved inwardly towards the center of said cam plate as said bobbin increases in diameter.

20 25 In testimony that I claim the foregoing I have hereunto set my hand at Basel, in the canton of Basel City and State of Switzerland.

ERNEST SCHWEIZER.

Witnesses:

PETER PROBST,
JULIA A. DURST.
